UNITED STATES PATENT OFFICE

136,798

DESIGN FOR A LOOSE-LEAF BINDER RING OR SIMILAR ARTICLE

John J. Seelman, Milwaukee, Wis., assignor, by
direct and mesne assignments, to Geo. Seelman
& Sons Co., Milwaukee, Wis., a corporation of
Wisconsin

Application February 5, 1943, Serial No. 109,468

Term of patent 14 years

To all whom it may concern:

Be it known that I, John J. Seelman, a citizen
of the United States, residing at Milwaukee, in
the county of Milwaukee and State of Wisconsin,
have invented a new, original, and ornamental
Design for a Loose-leaf Binder Ring or Similar
Article, of which the following is a specification,
reference being had to the accompanying draw-
ing, forming part thereof.

In the drawing:

Fig. 1 is a view in front elevation of a loose-
leaf binder ring or similar article showing my
new design.

Fig. 2 is a plan view of the loose-leaf binder
ring or similar article illustrated in Fig. 1.

I claim:

The ornamental design for a loose-leaf binder
ring or similar article, as shown.

JOHN J. SEELMAN.
